UNITED STATES PATENT OFFICE.

JOHN EDWIN PROSSER, OF TULSA, OKLAHOMA, ASSIGNOR TO PAUL ARBON, OF TULSA, OKLAHOMA.

SWIVEL-JAR WIRE-ROPE SOCKET.

1,045,883.

Specification of Letters Patent.

Patented Dec. 3, 1912.

Application filed May 2, 1912. Serial No. 694,725.

To all whom it may concern:

Be it known that I, JOHN EDWIN PROSSER, a citizen of the United States, residing at Tulsa, in the county of Tulsa and State of Oklahoma, have invented certain new and useful Improvements in Swivel-Jar Wire-Rope Sockets, of which the following is a specification, reference being had therein to the accompanying drawing.

10 This invention relates to apparatus used for the drilling of deep wells and especially to apparatus for use in drilling oil wells.

The invention more particularly relates to a swivel jar for wire rope.

15 It is characteristic of what is known as the Downie swivel jar that the lower end of the barrel or cylinder in which the jar member operates is formed integral with a part or member corresponding to what is

20 known as the subsocket, and hence the jar member or piston must be inserted through the upper and open end of the barrel. This open end is closed by a block screwing into the end of the barrel. This construction is

25 objectionable as the block is quickly torn out by the blows imparted by the jar or piston, and also for the reason that this block must be removed whenever it becomes necessary to connect a new rope to the jar or piston.

30 These objectionable features were overcome in the Brittan swivel, having the parts designed to receive the blows of the piston or swivel made integral with the barrel or cylinder, which has its lower end closed by the sub-socket screwing into such lower end.

In this construction this sub-socket must be removed in order to obtain access to the swivel for attaching a new rope or any other purpose.

35 And further in both the Downie and Brittan constructions the swivel or jar member has been formed with a hollow stem for the reception of the rope, said stem extending up through the hollow stem of the barrel or cylindrical portion of the device,

40 and in order that any air or foreign material which may enter the upper portion of the cylinder when the jar is down, can escape openings have been formed through the walls of the cylinder adjacent to its upper end.

45 It has been found in practice that openings sufficient in size and dimensions to permit of the escape of all air, etc., on the upward movement of the jar cannot be formed through the walls of the cylinder 50 without injuriously weakening it.

The invention described herein has for its object a construction of swivel jar having a hollow sub-socket formed integral with the barrel or cylinder, so as to permit of free access to the jar or piston when the swivel 60 jar is detached from the drill stem.

It is a further object of the invention to provide for the free escape of the air, sand and water, etc., in the direction of movement of the jar. And it is a further object of the 65 invention to provide for the maintenance of the rope from such contact with the stem of the body device, as will cause injury during its movement through such stem.

The invention is hereinafter more fully 70 described and claimed.

In the accompanying drawings, like characters of reference indicate like parts in the several views, and Figure 1, is a side elevation of a swivel jar wire rope socket constructed in accordance with this invention; Fig. 2 is a side elevation taken at right angles to Fig. 1; Fig. 3 is a vertical median section through the socket; Fig. 4 is an enlarged detail side elevation of the part of 80 the socket whereto the rope is secured, and Fig. 5 is an enlarged detail section showing the manner in which the movable part contacts with the tool carrying portion of the device.

This improved construction consists of two parts, which, for the sake of convenience, will be hereinafter termed the body or barrel and the swivel or jar. The body or barrel comprises a cylindrical central portion 10 below which is a portion 11 having flattened surfaces 12 at diametrically opposite points for the reception of a wrench or other holding means. Below these flattened portions the socket is again formed as a 90 cylinder 13, this latter being of uniform diameter with the cylindrical portion 10. Above the portion 10 of the body there is a frusto-conical portion 14 and the upper end of the body terminates in a cylindrical portion or stem 15 extending from the minor base of the frusto-conical portion. Intermediate its ends this cylindrical portion or stem 15 is provided with grooves 16 cut therearound so that the body may be engaged by a proper fishing tool. Each end of the body is preferably beveled as at 17.

Extending through the body is a bore. The central part of this bore extends from a point somewhat below the lower end of 110

the flattened portions 12 to a point below the frusto-conical portion 14 in a uniform diameter. This portion is indicated at 18 and below the portion is formed the usual internally threaded frusto-conical portion 19 for the purpose of attaching the bit or tool stem used in the drilling. Above the portion 18 the bore is continued as a reduced bore 20 and the shoulder between the portions 18 and 20 is beveled as at 21. If 10 found desirable several series of openings 22 and 23 may be formed through the wall of the portion 18 adjacent to its upper and lower ends.

15 The jar consists of a cylindrical body 24 of such size as to slidably fit within the portion 18 of the bore. The upper end 25 of this jar is frusto-conical in form so that it fits snugly against the shoulder 21. Through 20 this jar extends a bore, the upper portion of which is cylindrical in form, as indicated at 26 and is of less diameter than the bore 20 through the stem 15.

As the bore through the jar or piston is of 25 less diameter than the bore 20 through the stem 15, and as the upper end of the jar or piston is frusto-conical, the central portion of the jar or piston will be above the highest point of the piston striking against the 30 shoulder on the body portion, and hence a substantial body of metal is interposed between the rope and the portion of the piston which will be liable to be upset in the drilling operation. The lower portion of the 35 bore in the jar is frusto-conical in form, as indicated at 27 for the reception of the clip or clips 28 used for securing the end of the wire rope 29.

It is characteristic of my improved swivel 40 jar, that any blows or other strains imparted by the jar or piston is transmitted through an integral body of metal to the stem carrying the bit. Formerly when 45 using wire rope, the latter was connected by a swivel consisting of two or more parts to the jarring links consisting of two parts and there in turn were connected directly or by a sub-socket to the stem carrying the bit. Later improvements have reduced the 50 number of parts connecting the rope to the bit, by combining the swivel and jarring links, but in such combined structures, the blows of the piston or jar have been transmitted through threaded joints to the drill 55 or bit stem. As the drill stem and drill or bit have a combined weight of about three thousand pounds and as the weight is raised by a blow of the piston or jar on some part of the barrel it will be readily understood 60 that a threaded connection between such barrel and the parts to be lifted would be quickly destroyed, as has been found the case in practice. And further it is characteristic of this improved construction that 65 it is formed of only two parts which can

readily be separated for attaching new ropes or any other purpose. Furthermore, the bore portion 20 provides a guide for the rope 29 as the jar is moved up and down, the guide being sufficiently large so that under 70 ordinary circumstances the rope moves freely therein without any frictional engagement therewith. And further as the bore 20 is materially larger transversely than the rope and extends directly from 75 the upper end of the bore 18 in which the cylindrical jar operates, no air, liquid or other material can be pocketed between the upper end of the cylindrical jar and the shoulders 21, and hence the jar can strike 80 solidly against the shoulders 21.

It will also be noted that by reason of the bevel on the shoulder 21 and the end of the jar there will be no battering or upsetting of the shoulder by the end of the jar and 85 by reason of the opening 26 being smaller than the bore 20 the upper end of the opening 26 cannot be forced in against the rope by upsetting and thereby cutting in the rope at that point. It will be observed that the 90 diameter of the bore in the stem 15 is considerably greater than the external diameter of the rope, while the axial opening in the cylindrical jar is only slightly greater in diameter than the rope. By this construction 95 the jar, which is maintained centrally within the body portion, will hold the comparatively rigid rope centrally within the stem.

I claim herein as my invention:

1. In a two piece swiveling jarring device for well drilling apparatus, a body portion having a cylindrical bore extending with uniform diameter from its lower end and a rope guiding extension at its upper end and provided at the upper end of said bore with an annular shoulder, the wall of the bore at the lower end being outwardly inclined and internally threaded said shoulder and internally threaded portion being formed in 110 an integral body of metal in combination with a cylindrical jar or piston fitting loosely in the bore of the body portion, the jar or piston and the bore in the body portion being made of such relative lengths as 115 to afford such a length of movement to the jar or piston that a substantial blow or jar can be imparted to the body portion on the upward movement of the piston.

2. In a two piece swiveling jarring device 120 for well drilling apparatus, a body portion having a cylindrical bore extending with uniform diameter from its lower end and provided at the upper end of said bore with an annular shoulder and having a hollow 125 rope guiding extension at its upper end, the bore of the extension being of the same diameter as the opening through the shoulder, the wall of the bore in the body portion being outwardly inclined and internally 130

threaded at its lower end, the annular shoulder and internally threaded portion being formed in an integral body of metal, in combination with a cylindrical jar or piston arranged to rotate and reciprocate in the bore of the body portion, and having an axial opening of less diameter than that of the bore of the rope guiding extension, and means for securing a rope in such axial opening, the jar or piston being made of sufficient length to maintain the rope centrally in the guide extension and the bore in the body portion having such a length relative to the length of the jar or piston that the jar or piston will have sufficient stroke to impart a substantial blow or jar to the body portion on the upward movement of the jar or piston.

3. In a well drilling apparatus, the combination of a body portion having a cylindrical bore and provided with a hollow stem

having an internal diameter less than that of the bore in the body but greater than that of the rope to be employed, whereby a shoulder is formed at the junction of the 25 stem and body portion, a cylindrical jar arranged in the bore of the body portion and having such an external diameter relative to the internal diameter of the bore that the axes of the body portion and jar 30 may be maintained approximately in coincidence, said jar having an axial opening of less diameter than that of the bore through the stem of the body portion and means for securing a rope in said axial opening.

35 In testimony whereof I hereunto affix my signature in presence of two witnesses.

JOHN EDWIN PROSSER.
